UNITED STATES PATENT OFFICE.

WILLIS J. PERKINS, OF GRAND RAPIDS, MICHIGAN.

STARTING DEVICE FOR INTERNAL-COMBUSTION ENGINES.

1,145,435.

Specification of Letters Patent.

Patented July 6, 1915.

Application filed April 4, 1911, Serial No. 618,930. Renewed March 7, 1914. Serial No. 823,248.

To all whom it may concern:

Be it known that I, WILLIS J. PERKINS, a citizen of the United States, residing at Grand Rapids, Michigan, have invented certain new and useful Improvements in Starting Devices for Internal-Combustion Engines, of which the following is a specification.

This invention relates to improvements in starting devices for internal combustion engines, and it is particularly and especially well adapted for use on all manually operated starting devices for internal combustion engines, whether an automobile crank, a starting bar or lever, or other means, but may be adapted to power operated starting devices also.

The object of this invention is, in starting, to insure the firing time or electrical ignition period of the charge in an engine or any power unit of an engine at such predetermined relative position of piston with said firing time as to prevent a reverse rotation or back kick of the engine, its crank shaft or connected parts, thus avoiding accidents and damage from such reverse rotation.

Objects pertaining to details and economies of the construction, and details of the operation, will definitely appear from the description to follow.

I accomplish the objects of my invention by the devices and means described in the following specification.

The invention is clearly defined and pointed out in the claims.

A structure embodying the features of my invention in preferred form and various modifications, is clearly illustrated in the accompanying drawing, forming a part of this specification, in which:

Figure I is a view largely diagrammatic of my invention applied to the starting mechanism of an internal combustion engine as applied to an automobile. Fig. II is an enlarged detail sectional view on line 2-2 of Fig. I, showing details of the automatic cut-out switch. Fig. III is a detail plan view, taken on a line corresponding to line 3-3 of Fig. II, of the same automatic switch mechanism. Fig. IV is an enlarged detail view, partially in section, on line 4-4 of Fig. I, showing the action of the trip collar of the crank on the automatic cut-out switch. Fig. V is an enlarged detail sectional view on line 5-5 of Figs. I and VI, showing the switch means for controlling the regular cir-

cuit and special circuit cut-out of this device. Fig. VI is an enlarged detail sectional view on line 6-6 of Figs. I and V. Fig. VII is a diagrammatic view showing the circuits and the connection and wiring of the parts. Fig. VIII is an enlarged detail view of a modification showing the structure directly applied to a usual construction of an adjustable ignition timer. Fig. IX is an enlarged detail-sectional view on line 9-9 of Fig. VIII. Fig. X is a view of a modification of the structure where a detachable starting bar lever or crank is made use of for starting the engine. Fig. XI is a detail sectional view on line 11-11 of Fig. X.

In the drawings, the sectional views are taken looking in the direction of the little arrows at the ends of the section lines, and similar numerals of reference refer to similar parts throughout the several views.

Considering the numbered parts of the drawing, the engine 1 is of the usual internal combustion type with electric ignition, and is provided with a crank shaft 2 to which manual rotary motion may be applied for starting the same. A crank 3 is preferably made use of in starting, having a collar 4 on the crank shank or horizontal extension 8 for operating or tripping the cut-out switch device for breaking or disconnecting the main ignition circuit, which circuit includes the early spark. Suitably housed in a box 5 is a cut-out switch means consisting of the switch bar 6 carried by rock shafts 7, which is automatically urged against contact points 8-8' for closing the main sparking circuit 11. A tension spring 9 on the rock shaft 7 holds the switch 9 normally closed. An arm 10 on this rock shaft projects normally into the path of the trip collar 4 on the shank of the crank 3, so that when the crank 3 is inserted to lock in one direction with crank shaft 2 to start the engine, it will depress or move the arm 10 and operate the switch to break the circuit. The main circuit 11 includes the battery or other source of electric supply 12, and directly or indirectly the timer 24 and contact plate 14. This contact plate 14 is carried on an insulator plate 13, and a shorter contact plate 15 is arranged in proximity thereto on the under side thereof, as clearly appears in Fig. VI, or on the same side, as seen in Fig. VIII. An auxiliary cut-out circuit 16 leads from the contact 8' to the inde-

pendent insulated contact plate 15 (see Fig. VI). A slide switch 17, with contacts 17'-17" carried on suitable spring pressed arms 18-18 and suitably insulated therefrom, are 5 provided for connecting the contact plates 14 and 15 together. The contacts 17'-17" are joined by conductor 17''. The arms 18-18 are pivoted together on the timer connecting rod 19 (or any suitable movable 10 member of the ignition control system). This rod 19 leads from the spark controller rock shaft 20 of the steering column 23 of an automobile to the timer 24. The connecting rod 19 is here shown connected to the 15 rock shaft arm 21 on the rock shaft 20, and to the bell crank 22, which connects to the timer 24 by the link 22'. It will thus be seen that this sliding switch 17 is freely movable back and forth whenever the connecting rod 19 is moved. The contact plate 15 is so located relatively that it will only be connected to the plate 14 by the switch 17 when the timer 24 is set at the so-called late ignition period. From this description, 20 of the parts of the main structure, its operation will now be readily understood.

When the timer is set at the early spark, the switch 17 will be in the position indicated in Figs. I and VI. The late contact 25 plate 15 will not be included in the ignition circuit. If, now, the crank 3 be inserted, the collar 4 on the shank thereof will contact with the arm 10 and open the switch at 6. Because the timer is set at the early spark, 30 it will be impossible to produce an electric spark to start the engine, because the electric ignition circuit will be broken. If the timer is moved to the late spark before inserting the crank, the result will be that the 35 rod 19 will move toward the right of Fig. I, and the switch 17 will then electrically connect the plates 14 and 15. If, now, the crank is inserted, it will operate the switch 6, but this will not break the circuit because there 40 is a short or cut-off circuit 16 leading from the contact 8' to the plate 15 which is now connected with the plate 14 in the circuit to the spark plug through the timer. If the crank is now operated, the engine will be 45 fired at the late spark and there is no danger of the back kick or reverse rotation which has heretofore injured many persons and resulted in so much damage.

The above described form of my invention 50 may be used in motor vehicles operated by internal combustion engines and it eliminates the extending of all electric circuits or wires to the ignition controlling means, usually mounted on the ordinary steering 55 mast or adjacent thereto. I provide this form substantially as a merchantable accessory applicable to the majority of types of motor vehicles now in use. When the structure is included in the original design of internal combustion engines for motor ve-

hicles, its details may be refined and materially modified without departing from the spirit and scope of my invention. In some forms of ignition control, a portion of the device may be directly applicable to the 70 radially movable parts, as seen in Fig. VIII hereafter to be described, or in other forms it may be desirable to attach a portion of the device to intermediate co-acting parts, as rod 19, Fig. I. The principle and operation are similar. The difference is largely 75 one of convenience and utility.

In the modifications seen in Figs. VIII, IX, X and XI, I show the device radially operated by and incorporated into the common form of adjustable ignition timer devices. The connecting circuits shown in Figs. I and VII are connected in like manner to the parts shown in Figs. VIII and X. In Figs. VIII, IX, X and XI, I show the invention modified and especially adapted 80 to engines equipped with detachable manual starting devices. In Fig. VIII I show the adjustable timer 24 with the hand lever 25 projecting at one side, which is a common construction for engines. I provide the contact plates 14 and 15 arranged in proximity to the lever 25 and the switch bar 26, which corresponds to the switch 17 of my preceding construction, is disposed 85 beneath the timer lever 25. This switch bar is urged into contact with the contact plates 14 and 15 by a coiled spring 27, which is suitably carried on the under side of the lever 25, a recess 28 being formed in an 90 insulated block 29 for that purpose. The cut-out means for cutting out the early spark is operated by the starting bar 38, the weight of which, when it is put into position after the engine is started, closes the regular circuit and permits the setting of the timer to 95 get the early or late spark. In order, with this structure, when the starting bar 38 or detachable crank is removed from its support, to get the late spark it is necessary in 100 starting the engine to set the timer lever at the late spark. A block or rest 30, suitably located in relation to the engine, is provided, which carries the switch mechanism, which is operated by the weight of the starting lever bar or crank 38, or other starting means. Within this block 30 is a recess 105 31 for receiving the end of the starting bar. The switch bar 32 is carried on the forward end of the lever 34 by pivot 33 in the end of 110 the said lever 34. The lever 34 is fulcrumed at 35 and is held normally upward by spring 36. The rear end 37 of the lever forms a stop to retain the switch bar 32 in a slightly elevated position out of contact with the 115 contacts 8-8'. Any suitable support may be provided for the opposite end of the lever 38, so that when the lever 38 is in position, the main spark circuit, which includes the early spark circuit, is closed by the action 120 125 130

of its weight. When the lever bar or crank is lifted out of position, the regular early ignition circuit is broken. It is then necessary to obtain a current or spark to move the 5 timer lever to the late spark so that the cut-out circuit 16 will connect through switch bar 26 through plates 14 and 15 and enable the current to pass to the ignition device. The operation is then the same as previously 10 described, it being thus impossible to start the engine until the timer is set at the late spark.

That my claims may be clear, will state that by "main circuit" I mean the circuit 15 including the early spark. I do this because it is the circuit which is made use of after the engine is started and while it is doing its work. The circuit including the late spark only I denominate the "cut-out" circuit 20 because it cuts out that portion of the main circuit which includes the early spark. This circuit, however, embraces a portion of the same conductor and other devices as the main circuit.

25 The structures illustrated are all shown with jump spark timer devices. The structures are also adapted to the make and break devices as well. I do not deem it necessary to illustrate the same, as such changes as 30 may be needed to adapt the invention to such will be readily made by a skilled mechanician.

It is thus clear that my invention is capable of many embodiments. I believe 35 these shown are of special merit. I desire to claim the invention broadly, and also the preferred specific form as shown by the appended claims.

Having thus described my invention, 40 what I claim as new and desire to secure by Letters Patent is:

1. In a starting device for internal combustion engines, the combination of the engine; a crank shaft therefor; a disconnectable crank for operating the same; a main ignition circuit; a self-closing switch in the 45 said ignition circuit; disconnecting devices disposed to be acted upon by the crank when it is moved to the operative position for 50 breaking the said circuit; a timer in said main ignition circuit; a cut-out circuit connected at one end to the electric source side of the said self-closing switch and terminating at its opposite end in an automatic 55 switch consisting of a plurality of plates and a movable member; means for adjusting the said timer connected to the said automatic switch and adjusted to close the said automatic switch only when the timer 60 is set for a late spark, coacting substantially as described and for the purpose specified.

2. In a starting device for internal combustion engines, the combination of the engine; a crank shaft therefor; a disconnectable crank for operating the same; a main

ignition circuit; a self-closing switch in the said ignition circuit; trip devices to be acted upon by the crank when it is moved to the operative position for breaking the said circuit; a timer in said main ignition circuit; a cut-out circuit connected at one end to the electric source side of the said self-closing switch and terminating at its opposite end in an automatic switch; means for adjusting the said timer connected to the said automatic switch and adjusted to close the said automatic switch only when the timer is set for a late spark, coacting substantially as described and for the purpose specified. 70

3. In a starting device for internal combustion engines, the combination with the engine; means for imparting to the engine its initial motion; a main ignition circuit; a normally closed switch in the said ignition circuit; means for opening the same adapted 80 to be operated by the actuation of the starting means; a cut-out circuit connected at one end to the electric source side of the said normally closed switch; an automatic switch at the opposite end of said cut-out circuit 85 to connect the same to the main ignition circuit; a timer in the main ignition circuit; and means for adjusting the said timer connected to the said automatic switch and adjusted to close the said automatic switch 90 only when the timer is set for a late spark, coacting substantially as described and for the purpose specified. 95

4. In a starting device for internal combustion engines, the combination of the engine; means for giving the same initial movement; a main ignition circuit; a normally closed switch in the said circuit adapted to break the said circuit when the starting device is manipulated; a timer in the 100 said main ignition circuit; a cut-out circuit connected to the electric source side of the said switch in the main circuit, an automatic switch at the opposite end of said 105 cut-out circuit to connect it to the main circuit; and means for adjusting the said timer connected to the said automatic switch to close the said automatic switch only when the timer is set for a late spark, coacting as 110 described for the purpose specified. 115

5. In a starting device for internal combustion engines, the combination with the means for imparting to the engine initial movement, of a main ignition circuit; a timer device; a switch for breaking the main circuit when the said starting means is manipulated; an auxiliary circuit; a switch means for said auxiliary circuit to connect and include said auxiliary circuit in the main circuit; connections from said switch 120 to the timer to close the auxiliary circuit when the timer is set at the late spark and to open the said auxiliary circuit when the timer is set at the early spark, coacting for the purpose specified. 125

6. In a starting device for internal combustion engines, the combination with means for giving the engine its initial movement, of a main ignition circuit; a timer device; a 5 switch disposed to break the said circuit when the starting means is actuated; an auxiliary circuit; a switch for said auxiliary circuit disposed to control said circuits; connections from said switch to the timer to 10 close the said auxiliary circuit when the timer is set at the late spark and to open said auxiliary circuit when the timer is set at the early spark, coacting for the purpose specified.
- 15 7. In a starting device for internal combustion engines, the combination with means for imparting to the engine initial movement, of a main ignition circuit; means for breaking the said circuit disposed to break 20 the circuit when the starting means is manipulated; an auxiliary ignition circuit; means for closing the said auxiliary circuit; a timer; and connections from said timer to close the said auxiliary circuit when the 25 timer is set at the late spark, and to open said auxiliary circuit when the timer is set at the early spark.
8. In a starting device for internal combustion engines, the combination with means 30 for imparting to the engine initial motion, of a main ignition circuit; means for breaking the said circuit disposed to break the circuit when the starting means is manipulated; an auxiliary ignition circuit; a timer; 35 and means to close the said auxiliary circuit when the timer is set for a late spark and to open the same when set for an early spark.
9. In a starting device for internal combustion engines, an electric ignition device 40 comprising a source of electric supply and connections, with a suitable adjustable timer device for controlling the same; manually operated starting means for imparting initial movement to the engine; means disposed 45
- to be operated by the manipulation of the starting means to render the ignition means inoperative when the timer is set at the early spark; and means associated with the timer device to render the ignition means operative by the manipulation of the manually operated starting means whenever the timer is set at the late spark. 50
10. In a starting device for internal combustion engines, an electric ignition device 55 comprising a source of electric supply and connections, with a suitable adjustable timer, a device for controlling the same, manually operated starting means for imparting initial movement to the engine, means associated with the starting means to render the ignition means inoperative when the timer is set at the early spark, and means associated with the timer device to render the ignition means operative by the manipulation 60 of the manually operated starting means whenever the timer is set at the late spark. 65
11. In a starting device for internal combustion engines, the combination of electric ignition device comprising a source of electric supply and connections, with mechanical means for imparting to the engine initial motion, an advanced ignition circuit, a switch means for manipulating the said advanced ignition circuit, disposed to be 70 actuated to open said advanced ignition circuit when in the act of manipulating the starting means, and a retarding ignition circuit, a timer, and switch means associated with said timer to render inoperative the 75 said retarded ignition circuit when the timer is set for an advanced ignition spark. 80

In witness whereof, I have hereunto set my hand and seal in the presence of two witnesses.
